J. H. WILLIAMS.
COASTER PLANE.
APPLICATION FILED JAN. 2, 1919.

1,317,252.

Patented Sept. 30, 1919.

Inventor:
John H. Williams;

Robert H. Scamme,

Attorney.

UNITED STATES PATENT OFFICE.

JOHN H. WILLIAMS, OF CINCINNATI, OHIO.

COASTER-PLANE.

1,317,252.

Specification of Letters Patent. Patented Sept. 30, 1919.

Application filed January 2, 1919. Serial No. 269,190.

To all whom it may concern:

Be it known that I, JOHN H. WILLIAMS, a citizen of the United States, residing in the city of Cincinnati, in the county of Hamilton, State of Ohio, have invented a new and useful Coaster-Plane, of which the following is a full, clear, and comprehensive specification and exposition, the same being such as will enable others to make and use

10 the same with exactitude.

The object of my present invention, broadly speaking, is to provide a toy or child's vehicle formed to simulate an aeroplane, or the like, but adapted to travel upon 15 a floor or other comparatively smooth surface, or upon the ground, the same being strong and durable in construction, neat and attractive in appearance, easily operated and controlled, comparatively light 20 in weight, and which can be manufactured and sold at a comparatively low price.

Another object is the production of a coaster plane of novel construction and attractive in appearance, and adapted to aid 25 in the development of children and to contribute to their pleasure, at the same time providing a vehicle which will be very easy of propulsion and operation.

Other objects and advantages of the invention will suggest themselves in the course 30 of the following description, and that which is new will be correlated in the appended claim.

The preferred means for carrying out my 35 invention in a practical and a mechanical manner is shown in the accompanying drawings, in which—

Figure 1 is a side elevation of the complete construction. Fig. 2 is a plan view 40 of the same. Fig. 3 is a rear elevation of the device. Fig. 4 is a vertical detail section, as taken on the line 4—4 of Fig. 2. And Fig. 5 is a detail section taken centrally 45 through one of the supporting or ground wheels, showing the ball bearings therefor.

Similar indices denote like parts throughout the several views.

In order that the construction, the operation, and the advantages of the invention 50 may be more fully understood and appreciated, I will now take up a detailed description thereof, in which I will set forth the various features as fully and as comprehensively as I may.

55 Referring now to the drawings in detail: Numeral 1 denotes the main or central por-

tion of the body, whose forward portion terminates in the nose 2, and whose rear portion terminates in the tail 3, with an upwardly extending portion 4 having a relatively horizontal upper edge. The said parts 1, 2, 3 and 4, are formed by a single piece of material, having substantially the form shown in Fig. 1, and together simulating the fuselage of an aeroplane.

Formed vertically through the forward portion of the body 1 is an aperture in which is rotatably mounted the steering rod or pipe 5, which projects above and below the member 1, as in Fig. 4.

The forward truck carriage includes downwardly and outwardly diverging arms 6, each terminating in a vertical wheel-plate 7, and an upwardly extending central collar 8, in which latter is located the lower 75 end of the pipe 5 where it is rigidly secured by the bolt 9 which passes through the collar 8 and the pipe 5.

Extending outward divergently and horizontally from each of the plates 7 are the 80 spindles 10 and 11 on which are frictionlessly mounted the respective ground wheels 12 and 13, the ball-bearings for which are denoted by the numeral 14 in Fig. 5.

The upper horizontal surface of the collar 8 is in bearing contact with the lower edge of the member 1.

Numeral 15 denotes the steering-post having a central cavity in its lower end portion in which is tightly fitted the upper 90 end of the pipe 5. A bolt 16 is inserted through the post 15 and the pipe 5 to prevent them turning with relation to each other. Also a cut 17 is formed in the post 15, extending upward longitudinally of the 95 post from its lower end, in order that when the bolt 16 is tightened then the post 15 will be clamped about the pipe 5 to retain them rigid with relation to each other.

A handle-bar 18 is secured in the upper 100 portion of the post 15, whereby the device may be guided by hand. By the above it is apparent that the front truck is swivelly mounted.

The rear truck carriage is rigidly connected to the body member and it includes the downwardly and outwardly diverging arms 19, each terminating in a vertical wheel-plate 20, and having upwardly extending spaced apart flanges 21 between 110 which fits the rear portion of the body 1. Said flanges 21 being secured to the body

1 by the bolt 22, substantially as shown, or by screws.

Extending outwardly and horizontally from each of the plates 20 are the spindles 5 29 and 30 on which are frictionlessly mounted the respective wheels 31 and 32, the ball-bearings for which being of the same character as that for the front wheels as shown in Fig. 5.

10 Secured horizontally on the upper edge of the extension 4 is the seat 23, the same being attached by the screws 24. Said seat is further supported by the braces 25.

Numeral 26 denotes the horizontal wing 15 member which extends an equal distance on each side of the body 1, or the nose 2, to the upper edge of which it is secured by the screws 27. The central rear portion of the member 26 is curved inward whereby it will 20 stride the post 15, but without contact therewith. Said wing member 26 is further supported by the braces 28.

Projecting forward and slightly upward from the terminal of the nose 2 is the spindle 25 33 on which is revolvably mounted the propeller wheel 34. The hub of the wheel being frictionlessly mounted, by ball bearings on the spindle 33 in the same manner as the ground-wheels are mounted.

30 A small socket or cavity 35 in the tail portion, in which may be placed the point of a cane or an umbrella by which the device may be pushed by a person walking in the rear thereof.

35 In practice a child may be seated on the seat 23, with his legs astride the body 1, with his hands engaged with the handle-bar 18. Then he can tread the ground, or the floor, with his feet in such manner as

40 to propel the device forward. And by turning the post 15 with the handle bar he may direct the device in the direction desired. After attaining the desired speed, or upon a down grade, the device with the rider

45 will travel a considerable distance without applying propelling force, at which time the rider may rest his legs on the wings 26, with his feet on each side of the propeller 34. When traveling forward it is evident

50 that the resistance of the air will cause the propeller wheel 34 to revolve, appearing in

practice to be furnishing the propelling force to the device as it glides forward.

From the above it is evident that the device in action will simulate an aeroplane, 55 as the revolving propeller 34, the shape of the body, and the wings 26, will help to carry out that idea in a very realistic manner.

When not in use, and in order to utilize 60 space, the device may be stood on its rear end or tail 3 and with the wheels 31 and 32 also resting on the floor, and with the propeller uppermost.

I desire that it be understood that various 65 changes may be made in the various details of construction, without departing from the spirit of the invention, and without sacrificing any of the advantages thereof which are new and useful.

Having now fully shown and described my invention, what I claim and desire to secure by Letters Patent of the United States, is—

A coaster plane having a one-piece body 75 whose termini form a nose and a tail and all formed to simulate the fuselage of an aeroplane, a rear truck having flanges striding the lower edge of said body and arms projecting divergently downward and terminating in wheel-plates, spindles carried by the said wheel-plates, and a ball-bearing wheel mounted on each of said spindles, a front truck comprising a collar, arms extending divergently downward from the 80 collar and terminating in wheel-plates, spindles extending out from the wheel-plates, and a ball-bearing wheel mounted on each spindle, a steering-rod secured in said collar and extending upward through the body, a 85 steering post secured to the upper end of the steering-rod, a handle-bar carried by said post, wings extending across the body and located near the steering-post, and a seat secured to said body and located in the rear of said wings, all substantially as set forth.

JOHN H. WILLIAMS.
